SOLDER DISPENSING PACKAGE

Manis Wessen, New York, N.Y., assignor to Rayline, Inc.,
Mineola, N.Y., a corporation of New York

Filed Sept. 15, 1965, Ser. No. 87,041

Term of patent 14 years

(Cl. D58—2)

FIG. 1

FIG. 2

FIG. 3

The rolled solder shown in broken lines is depicted for illustrative purposes only.

I claim:

The ornamental design for a solder dispensing package, as shown and described.
